ADJUSTABLE CLAMPING FIXTURE FOR WORK BENCHES

Filed Sept. 13, 1944

Viktor Grünler

UNITED STATES PATENT OFFICE

2,439,151

ADJUSTABLE CLAMPING FIXTURE FOR
WORKBENCHES

Viktor Spinnler, Zurich, Switzerland

Application September 13, 1944, Serial No. 553,900

1 Claim. (Cl. 144—303)

1

The present invention relates to a clamp for fixing work pieces of any kind, especially of wood, such as boards, fillets and the like, and an object of the invention is, first, to provide a clamp with one stationary and one movable gripping jaw, and with a fixing device provided with an eccentric clamping lever operated by canting, for the purpose of locking the movable clamping jaw and thus clamping the work piece between the two jaws; second, to provide means for a vertical adjustment by which the upper edge of the clamping jaws can be lowered to the level of the top of the work table; third, to provide a movable tool which may transform any plain table into a full joiner's bench, thus representing a perfect substitute for a planing bench.

The accompanying drawing illustrates two forms of construction:

Figure 1 shows a side elevation of the clamp mounted on a table top according to the first form of construction as seen in the direction of the arrow I of Figure 2;

Figure 2 is a top plan view of the clamp and table top shown in Figure 1, seen in the direction of the arrow II of Figure 1;

Figure 3 is an end elevational view as seen in the direction of the arrow III of Figure 1;

Figure 4 shows a section on the line IV—IV of Figure 2, with the movable clamping jaw and lever in another position;

Figure 5 is a top plan view of a second form of construction of a holder for the clamp having two clamp-guides.

In the construction shown in Figures 1 to 4, number 1 indicates a stationary, preferable wooden, gripping jaw of a clamp. This clamping jaw has a downward extension 2 with a barlike carrier 3 fixed thereon by means of screws 4, said carrier being at right angles to the clamping jaw 1 and its extension. Number 5 designates the movable clamping jaw, likewise made of wood, said jaw being fastened through a screw 6 onto an angle iron 7 which is welded onto a sliding member 8, the latter being within certain limits movable along a slot in a support 9 in a direction in which the clamping pressure is applied to the jaw 1. Number 10 denotes an oscillating lever, its fulcrum being at 11 in the support 9. This lever has an eccentric portion terminating in a projection or nose 12, said eccentric being operatively connected with the angle-iron 7. The slide 8 bears a pin 13 intended to cooperate with the projection 12 of the eccentric in the manner described hereafter. The support 9 is slidable along the bar-like carrier 3 by reason of an aper-

ture therein through which the carrier is inserted, said aperture being provided with two tipping edges 14 and 14' located on opposite sides of said carrier and at a slight axial distance a from each other.

15 designates a holder for the clamp, this holder possessing four laps 16 and 17 intended for sliding over a table top 18. Two fixing screws 19 serve respectively for loosening and tightening 10, the clamp holder 15 on the table top 18. The holder 15 is provided with a guide-bed 20 for receiving the extension 2 of the clamping jaw 1, said extension being vertically adjustable in the guide-bed 20, and being adapted to be secured at any position of elevation by means of the clamping screw lever 21.

The manipulation and function of the clamp is as follows:

First, the holder 15 is conveniently mounted 20 on a table top 18, whereupon the extension 2 of the clamping jaw 1 is inserted into the guide-bed 20 of the holder 15 and tightened in the required vertical position by means of the clamping screw lever 21. The wooden work piece, for instance a plank 22, is then inserted between the jaws so that it rests simultaneously on the table top 18. The support 9 with the clamping lever 10 is thereupon shifted from the position shown in Figure 1 in the direction of the arrow III until 25 the clamping jaw 5 lies adjacent the plank 22, whereupon the lever 10 is moved in the direction of the arrow A indicated in Figure 1, thus forcing the jaw 5 away from the pivot of the eccentric 12 of lever 10, and pressing it in the direction 30 of the arrow III of Figure 1—firmly against the work piece 22. Due to the clamping pressure thus set up adverse to the direction of arrow III, the support 9 on carrier 3 tilts, and owing to the only slight axial displacement a of the tipping edges 35 40 the clamping pressure conveyed to the edges 14 and 14' is increased so as to cause self-impediment, the support being held fast, friction-tight on the carrier 3. Since the eccentricity of the eccentric 12 is a comparatively slight one, there 45 likewise exists—in the position of the eccentric as seen from Figure 4—self-impediment between eccentric and angle iron 7 so that the lever 10, without further effort, remains locked in the position shown in Figure 4. The work piece 22 is 50 now tightly grasped by the clamp on both sides with its edge resting on the table top 18, thus ensuring a firm hold of the work piece. The work piece 22 can now, for instance, be planed, sawed, drilled, polished, filed, rasped or otherwise treated.

If the clamping connection is to be loosened again, the lever 10 is raised opposite to the direction indicated by arrow A, the projection 12 of the eccentric pushing against the pin 13 to cause a displacement of slide 8 in the opposite direction of the arrow III indicated in Figure 1, the clamping jaw 5 being thereby withdrawn from the work piece 22.

The clamp-holder as shown in Figure 5 is provided with two guide-beds 20, 20' for selectively receiving the extension 2 of the clamp, the arrangement of said guide-beds towards each other being such as to cause the longitudinal axes (shown in Figure 5 by dash-and-dot lines) of the cross sections of the guide-beds to run at right angles to each other. If the clamp is set into the guide-bed 20' it can conveniently be used as an ordinary vise.

While I have herein illustrated and described certain preferred embodiments of the present invention, it will be apparent that changes in the construction and operation thereof may be made without departing either from the spirit of the invention or its scope as claimed hereafter.

I claim:

An attachment of the character described comprising, in combination: a clamp including a stationary jaw having an extension arm, a carrier bar extending laterally from the side of the extension arm adjacent said stationary jaw, an adjustable mount having an aperture to receive said carrier bar therethrough and having tipping

edges on opposite walls of said aperture adapted to effect locking engagement of said bar upon canting of said mount, an engaging jaw disposed for limited sliding movement along said mount, an eccentric locking device adapted to urge said slideable jaw against an engaged work piece and thereby cant said mount upon said carrier bar, a clamp holder having means for attachment to a table top and having a guide bed adapted to receive said clamp extension arm therein, said guide bed having an upper edge disposed below said table top so that said jaws may be positioned substantially flush with said table top, and locking means on said guide bed for securing said extension arm at selected positions of vertical adjustment therein.

VIKTOR SPINNLER.
